(57) **CLAIM**

The ornamental design for a vacuum cleaner, as shown and described.

DESCRIPTION

FIG. 1 is a perspective view of a vacuum cleaner, showing my new design;

FIG. 2 is a front elevation view thereof;

FIG. 3 is rear elevation view thereof;

FIG. 4 is a right side elevation view thereof;

FIG. 5 is a left side elevation view thereof;

FIG. 6 is an enlarged top plan view thereof;

FIG. 7 is an enlarged bottom plan view thereof;

FIG. 8 is another perspective view thereof, showing the upper portion of the vacuum cleaner detached from its lower portion for clarity of illustration;

FIG. 9 is a front elevation view thereof;

FIG. 10 is rear elevation view thereof;

FIG. 11 is a left side elevation view thereof;

FIG. 12 is a right side elevation view thereof;

FIG. 13 is an enlarged top plan view thereof; and,

FIG. 14 is an enlarged bottom plan view thereof.

The broken lines illustrate portions of the vacuum cleaner that form no part of the claimed design.

1 Claim, 10 Drawing Sheets
